RICHARDT VILHELM EMIL RASMUSSEN, OF EMDRUP, DENMARK.

DOUBLE PLOW.

SPECIFICATION forming part of Letters Patent No. 728,010, dated May 12, 1903.

Application filed December 7, 1901. Serial No. 85,114. (No model.)

To all whom it may concern:

Be it known that I, RICHARDT VILHELM EMIL RASMUSSEN, a subject of the King of Denmark, residing at Emdrup, in the county 5 of Copenhagen, in the Kingdom of Denmark, have invented a new and Improved Double Plow, of which the following is a specification.

This invention relates to double plows designed especially for plowing on inclined surfaces, as the sides of hills, and constructed to be used in either direction and having the beam mounted to turn to coact with either share.

The invention consists of novel features 15 and parts and combinations of the same, as will be fully described hereinafter and then pointed out in the claim.

In the accompanying drawings, forming a part of this specification, Figure 1 is a side 20 elevation of the improvement. Fig. 2 is a plan view, and Fig. 3 is a detail view, of the latch device.

B is a cross-bar, with which the plowshares A' A² are connected. A shaft or pivot C rests 25 at its lower end in a bearing on the plow and extends upwardly through a bearing G on the cross-bar B and terminates at its upper end in the plow-beam K.

L represents the plow-handles, extending 30 in an opposite direction to the plow-beam and connected with the same at its junction with the pivot or shaft C.

Connected with the plowshares are two uprights D' D², each of which is formed with a 35 recess in one of its side faces adapted to receive the plow-beam. Latches E' E² are pivoted at their upper ends on said uprights, and keepers F' F² are arranged to engage said latches. When it is desired to reverse the 40 direction of travel of the plow, one of the latches—for instance, E'—is moved out of engagement with the beam and the beam is turned to an engagement with the upright D² and is fastened in this position by the latch E².

To equalize the draft on the plow, no matter in which direction it is drawn, the following arrangement is employed: The plow-beam K is provided at its forward end with a vertically-arranged segmental head having a series of apertures formed therein. A clevis 45 P is pivotally connected at its rear end with the beam by a bolt N, and a bolt O is ar-

ranged to pass through an aperture in the clevis near its forward end and through any one of the apertures in the head of the beam 55 to vertically adjust the clevis. The forward end of the clevis is horizontally enlarged, forming a loop. The draft-hook S is connected with an arm R, arranged to turn on a bolt Q, so that the hook S can be moved to either 60 side of the loop of the clevis, and thus correspond in lateral position with the share relative to the beam. The parts being arranged as shown in Fig. 1 after a furrow is made in one direction, then the latch E' is turned up 65 and the driver turns the team sufficiently to cause the beam K to move into engagement with the upright D² below the latch E², which is then turned down to locking position. The hook S, with the arm R, is then turned to the 70 opposite side, and the plow is ready to cut another furrow in the opposite direction.

The plow works easily, the position of the beam can be quickly changed, and the latch devices employed securely hold the beam in 75 position.

The plowshares are preferably so arranged that their lower edges form an obtuse angle with one another, as shown in Fig. 1, so that the lower side of the rear plow, or the one 80 not at work, is always slightly elevated. The plowshares instead of having the usual form may have the form shown in Fig. 2.

The uprights D' D² each carries a knife, as shown in Fig. 1, for dividing the green turf 85 in front of the plow.

Having now described my invention, what I claim as new, and desire to secure by Letters Patent, is—

A double plow, comprising uprights connected with the plowshares and each having a recess in its face, a common beam having a vertical portion at one end forming a shaft mounted between the shares, so that the beam can be swung into engagement with the recess of either of said uprights, and a latch pivoted to each upright and adapted to engage a keeper to lock the beam in position. 90 95

In witness whereof I have hereunto set my hand in the presence of two witnesses.

RICHARDT VILHELM EMIL RASMUSSEN.
